UNITED STATES PATENT OFFICE.

JOHN LOCHNER, OF NEW YORK, N. Y., ASSIGNOR TO THE NORWALK LOCK COMPANY, OF SOUTH NORWALK, CONNECTICUT.

DESIGN FOR ORNAMENTATION OF BUILDERS' HARDWARE.

SPECIFICATION forming part of Design No. 16,892, dated September 7, 1886.

Application filed June 14, 1886. Serial No. 205,145. Term of patent 7 years.

To all whom it may concern:

Be it known that I, JOHN LOCHNER, of New York, in the county of New York and State of New York, have invented a new Design for the Ornamentation of Builders' Hardware; and I do hereby declare the following, when taken in connection with accompanying drawing and the letters of reference marked thereon, to be a full, clear, and exact description of the same, and which said drawing constitutes part of this specification, and represents a face view of a door escutcheon-plate.

This invention relates to a design for the ornamentation of builders' hardware, such as used for house-trimmings; and it consists in a plain border upon the article, representing a panel, and upon the face of the panel a tracery represented as made from twisted cord, and as shown in the accompanying illustration.

In the illustration I show an escutcheon-plate for a lock and knob latch, which will be sufficient to illustrate the design for other analogous articles of house-trimmings. Around the article is a plain margin, *a*, forming a panel on the surface. The surface of the panel

is ornamented by a tracery represented as made from a twisted cord or rope, as clearly shown in the accompanying illustration. On the surface, in addition to the twisted cord-like ornamentation, there is the representation of floriated tracery branching from the cord-like stem. This branching tracery, however, may be varied to a considerable extent without departing from this invention, the essential feature of which is the tracery consisting of the representation of a twisted cord combined with floriated tracery branching therefrom.

I claim—

The herein-described design for the ornamentation of builders' hardware, consisting in a tracery on the surface of the article, represented as made from twisted cord or rope, with floriated branches springing therefrom, as described and shown.

JOHN LOCHNER.
